UNITED STATES PATENT OFFICE

RICHARD B. BROWNE, OF BROOKLYN, NEW YORK

BALANCED WINDOW SASH

Application filed January 27, 1932. Serial No. 589,101.

The object of my invention is to provide sashes which are self contained and will automatically hold themselves at any desired level and which may be raised or lowered by 5 grasping any portion of the sash. This and other objects are accomplished by my invention, one embodiment of which is hereinafter more particularly set forth.

For a more particular description of my 10 invention, reference is to be had to the accompanying drawings forming a part hereof in which

Figure 1 is a sectional view of a sash and a portion of a window frame embodying my 15 invention. The section is taken on the line 1-1 of Figure 3, looking in the direction of the arrows;

Figure 2 is a sectional view on the line 2-2 of Figure 1, looking in the direction of 20 the arrows;

Figure 3 is a longitudinal section of a window provided with my improved sash;

Figure 4 is an enlarged sectional view taken on the line 4-4 of Figure 3, looking 25 in the direction of the arrows;

Figure 5 is a diagrammatic view showing rails and rollers for a lower sash; and

Figure 6 is a corresponding view for an 30 upper sash, the rollers in each case in dotted circles indicating the opposite from the closed position; and

Figure 7 shows a window with two sashes embodying my invention, the interior mechanisms being omitted, except that rollers are 35 shown in dotted lines.

Throughout the various views of the drawings, similar reference characters designate similar parts.

In the preferred embodiment of my invention, 40 my improved window 1 has a frame 2, an upper sash 3, and a lower sash 4. The sashes are provided at suitable positions with angle metal strips 5, which hold packing 6 45 in the conventional manner, or in any desired

manner, so as to make a weather tight joint wherever desirable.

The frame 2 is conventional in all respects except that in each style are rails 7 and 8, the former for the lower and the latter for 50 the upper sash. The form of these rails can best be gathered from Figures 5 and 6. The rail 7 has a lower roller 9 and an upper roller 10 and correspondingly, the rail 8 has a lower roller 11 and an upper roller 12. Each rail 55 is divided into two parts so that each roller runs on one part only and these parts are connected by a horizontal line. These rollers, as will appear below, are pivotally mounted and spring pressed in their respective sashes, 60 so that they press against their respective tracks. And it will be noted that at the top and bottom, these rollers rest in slight depressions, and that between these depressions, 65 these tracks are not straight but are inwardly curved, something like one-sixteenth of an inch in two feet, so as to compensate to some extent for the compressions of the springs, 70 as the rollers run on their tracks. This curvature is particularly noted, because, although it is slight and hard to show in a drawing, it is particularly important in the functioning 75 of the apparatus for reasons which will appear below.

In the embodiment of my invention which is shown herein, the sashes 3 and 4 have hollow frames which are preferably made of sheet metal 13, but may be made in any suitable way. Glass 14 is held in these frames in the conventional manner, so that no further description of this detail is necessary. In the vertical tubing of each frame and near the corner thereof, as indicated in Figure 1, is placed a pivot 15 which is supported by the frame or a re-enforcement thereof. On this 80 pivot is a link 16 which runs to a pivot 17 of a roller 9 or 10, as the case may be. These pivots also turn in suitable spring caps 18, each of which has a post surrounded by a coil spring 19 that runs to a rod 20 with a collar 90

21 thereon against which the spring rests. These rods have at their inner ends right and left nuts 22 to receive and fit corresponding threads on a right and left screw 23 so that 5 by turning this screw the tension on the springs 19 may be varied. Each nut 22 has a lug 24 extending laterally therefrom so as to prevent it from turning in the case 13. A suitable opening 25 (see Figure 4) is made in 10 the casing 13 to give access to the holes in the right and left screw 23 for the purposes of this adjustment.

The spring caps 18 are also provided with laterally extending ears 26 to which are pivotally connected the equalization links 27 which, at their inner ends, are pivotally connected to an equalizing lever 28 pivotally mounted on a bracket 29 fixed to the interior of the casing 13. This construction equalizes 20 the tension of the springs 19 so that an equal tension is on the wheels 10 or the wheels 9.

It is desirable that the wheels 9, 10, 11 and 12 be mounted on spindles 17 through the agency of ball bearings so as to reduce friction 25 to a minimum.

The mounting of the rollers 11 and 12 in the upper sash 3 is precisely the same as the mounting of the rollers 9 and 10 in the lower sash, and the spring systems and equalizing systems are the same in each. 30

It is apparent from the foregoing that the inclination of the rails 7 and 8 causes the springs 19 to have decreased tension as the sashes are raised and increased tension as the 35 sashes are lowered. By actual experience, it was found that when the rails 7 and 8 were straight, the rollers riding thereon, spring pressed as above stated, functioned irregularly and badly and it was impossible to hold 40 a sash in any position if the sash were mounted on rollers with a minimum friction so that they could move easily. This difficulty was overcome by curving the rails 7 and 8 slightly inwardly as above specified, and the equalizing 45 mechanism also favored a proper functioning of the rollers, the two means together giving a perfect result. At the extreme ends of their runs, the rollers on the rails 7 and 8 are placed in slight depressions so that a 50 slightly increased pressure is required to shift the sashes when at their extreme positions. This is desirable but not essential. It has been found by experience that the sashes made as above described shift so freely and easily 55 that it is desirable to hold them as above indicated at their extreme upper and lower positions.

In view of the foregoing, the operation of 60 my invention will be readily understood. To shift a window, it is necessary to exert a very slight pressure at any part of the window in the direction in which it is desired to move it, and after the start, even this slight pressure is reduced and the windows may be easily 65 stopped regardless of their weight at any

desired elevation, and will hold the positions into which they are set.

While I have shown and described one embodiment of my invention, it is obvious that it is not restricted thereto, but that it is broad 70 enough to cover all structures that come within the scope of the annexed claims.

Having thus described my invention, what I claim is:

1. In a window of the class described, a 75 sash, curved tracks within the window frame adjacent to said sash, spring pressed rollers running on said tracks, links each pivotally connected at one end to the sash and at the other to a roller and extending in the direction of movement of said sash and means for equalizing the pressure of said rollers on said tracks whereby the weight of the sash is counterbalanced evenly at different levels.

2. In a window of the class described, a 80 sash, curved tracks contained within the window frame alongside said sash, spring pressed rollers running on said tracks, links connecting said rollers and sash, and means for adjusting the tension of the springs pressing 90 the rollers.

3. In a window of the class described, a sash, curved tracks with tapered ends contained within the window frame alongside 95 said sash, spring pressed rollers running on said tracks, and links connecting the rollers and sash, whereby the sash may be held at certain levels with no more than normal stress.

4. In a window of the class described, a 100 sash, curved tracks contained within the window frame alongside said sash, and spring pressed rollers at the top and bottom of said sash, these rollers being connected to the sash by means of links.

5. In a window of the class described, a sash, tracks within the window frame which tracks slightly diverge from each other, spring pressed rollers running on said tracks, each roller having a suitable support and being connected to the sash by a link pivoted thereto at one end and to the roller support at the other, and means for equalizing the pressure of the rollers on said tracks. 110

6. In a window of the class described, a 115 sash, divergent tracks within the window frame, and a pair of spring-pressed rollers running on said tracks and having each a suitable support, one roller being connected to one side of said sash by a link pivoted thereto at one end and to the roller support at the other, and the other roller being similarly connected to the other side of said sash. 120

7. In a window of the class described, a sash, tracks within the window frame, a pair 125 of spring-pressed rollers running on said tracks and having each a suitable support, links each pivoted at one end to said sash and to a roller support at the other, and means for equalizing the pressure of said 130

rollers on said tracks, said means comprising a pair of links each connected at one end to a roller and at the other to its companion link through an equalizing member.

- 5 8. In a window of the class described, a sash, tracks within the window frame adjacent to said sash, a pair of rollers at the top of said sash and a second pair at the bottom thereof, each roller having a suitable support and being connected to said sash by a link pivoted thereto at one end and to the roller support at the other.
- 10

In testimony whereof, I have hereunto set my hand this 26 day of January, 1932.

15 RICHARD B. BROWNE.
